UNITED STATES PATENT OFFICE.

OSCAR A. OLSON AND WALTER OLSON, OF LEADER, MINNESOTA.

INTERNAL-COMBUSTION ENGINE.

1,257,104.

Specification of Letters Patent. Patented Feb. 19, 1918.

Application filed May 26, 1916. Serial No. 100,065.

To all whom it may concern:

Be it known that we, OSCAR A. OLSON and WALTER OLSON, citizens of the United States, residing at Leader, in the county of Cass 5 and State of Minnesota, have invented new and useful Improvements in Internal-Combustion Engines, of which the following is a specification.

This invention relates to internal combustion engines of the double acting two cycle type, the object in view being to produce an engine embodying a novel arrangement of pistons operating within a single cylinder and so connected with the crank 15 shaft that two explosions or impulses occur in each complete cycle of the engine thereby giving a more continuous torque to the crank shaft of the engine and producing a maximum amount of power with 20 a minimum amount of weight, also obtaining compactness and unusual strength for the entire structure.

With the above and other objects in view, the invention consists in the novel construction, combination and arrangement of parts, 25 as herein described, illustrated and claimed.

In the accompanying drawings:—

Figure 1 is a section taken diametrically of the cylinder of the engine, showing the 30 arrangement of the pistons therein and the relation of said pistons to the single crank shaft to which all of them are connected.

Fig. 2 is a similar view showing the pistons at the opposite ends of their throw.

Fig. 3 is a cross section on the line 3—3 of Fig. 1.

Fig. 4 is a cross section on the line 4—4 of Fig. 1.

In the engine illustrated in the accompanying drawings we have shown a single cylinder 1 as that is all that is necessary to an understanding of this invention, it being obvious that as many cylinders may be employed as required to give the desired power.

The crank shaft 2 has a single crank 3 to which is coupled a connecting rod 4 having a pivotal connection with the adjacent extremity of a piston rod 5 extending centrally and longitudinally within the cylinder and operating through a stuffing box 6 in the head thereof adjacent to the crank shaft 2. The piston rod 5 has fixedly mounted thereon two pistons 7 and 8 arranged in spaced relation to each other and

movable toward and away from the heads 9 and 10 of the cylinder 1.

The crank shaft 2 is provided with other cranks 11 arranged at opposite sides of the crank 3 and preferably offset one hundred 60 and eighty degrees therefrom as clearly shown in Figs. 1 and 2, each of the cranks 11 having coupled thereto a connecting rod 12 which is pivotally connected to a piston rod 13 working through one of a pair of stuffing boxes 14 in the cylinder head 10. The piston rods 13 operate in unison and carry at their free ends a third piston 15 which moves back and forth between the pistons 7 and 8. The piston 15 is fixedly 70 mounted on both of the rods 13 and the latter pass through openings in the piston 8 where they are surrounded by packing rings 16 similar to those used in connection with the outer periphery of a piston. The piston 15 is also formed with a central opening 75 through which the piston rod 5 passes, the latter being surrounded by other packing rings 17 to prevent leakage.

At their outer ends the piston rods 13 80 are supported by cross heads 18 which move between cross head guides 19 shown as fastened to the cylinder head 10. The cylinder is provided with a central exhaust port 20 opened and closed by a mechanically 85 operated and properly timed exhaust valve 21. Any suitable means may be employed for actuating and properly timing the exhaust valve 21. The cylinder is also provided with spark plugs 22 arranged adjacent to 90 the inlet ports 23 and 24. At its opposite ends and immediately adjacent to the cylinder heads 9 and 10, the latter is provided with ports 25 which communicate with by-passes 26 leading to the inlet ports 23 and 95 24, the by-passes 26 being formed with internal valve seats 27 in conjunction with which operate spring closed check valves 28.

29 represents a carbureter connected with an intake manifold the branches 30 of which 100 lead to opposite ends of the cylinder 1, the latter being formed adjacent to the opposite heads thereof with admission ports 31 to permit fresh charges of explosive mixture to enter the end portions of the cylinder in which the charges are compressed. Spring closed check valves 32 control the admission ports 31.

In operation, the mixture admitted through the manifold 30 and past the check 110

valves 32 is drawn into the compression chamber 33 as the piston 7 moves inwardly toward the piston 15 and, while the latter is being driven outwardly during the explosion which takes place between said piston 15 and the piston 8. In the return or outward movement of the piston 7, the charge previously drawn into the chamber 33 is compressed and forced through the port 25 past the check valve 28 and through the by-pass 26 into the combustion chamber 24 between the pistons 7 and 15. When the pistons 7 and 15 are at the nearest point to each other as shown in Fig. 2, a spark is created by the plug 22 thereby exploding compressed mixture between the pistons 7 and 15 and driving them in opposite directions. The same operation applies with respect to the pistons 15 and 8. The piston 8 drawing in the mixture as it moves inwardly and compressing the mixture as it moves toward the adjacent cylinder head, forcing the mixture through the respective by-pass 26 into the combustion chamber 25 between the pistons 8 and 15. These pistons as they move toward each other compress the charge and as they reach the nearest position to each other the charge is exploded by the adjacent plug 22 thus driving the pistons 8 and 15 in opposite directions.

It will thus be seen that in each revolution of the crank shaft 2, there are two explosions one of which drives the piston 8 toward the head 10 of the cylinder and the other of which drives the piston 7 toward the head 9 of the cylinder.

In view of the foregoing description, an exceedingly light, compact and powerful engine is employed, in which, while only one cylinder is used, there are two impulses in each complete revolution of the crank

shaft. It will of course be understood that one, two or more of the power units hereinabove described may be employed in connection with a single crank shaft according to the total amount of power required for any given purpose. These and other changes in the form, proportion and minor details of construction may be resorted to without departing from the principle or sacrificing any of the advantages of the invention.

We claim:—

An internal combustion engine comprising a cylinder, heads closing both ends of said cylinder, a crank shaft, a piston rod extending centrally and longitudinally of said cylinder and integrally coupled to said crank shaft, two pistons fixedly mounted on said piston rod in spaced relation to each other and each operating entirely at one side of a central exhaust port in the cylinder, an independently movable third piston interposed between said pistons and dividing the cylinder so as to form two combustion chambers and two compression chambers the outer walls of which are formed by the cylinder heads, the cylinder being also provided with by-passes affording communication between the said compression chambers and combustion chambers, and piston rods secured directly to said third piston through one of the first mentioned pistons and connected by rods directly to cranks of the crank shaft offset in relation to the crank to which the central piston rod is coupled.

In testimony whereof we affix our signatures.

OSCAR A. OLSON.
WALTER OLSON.
